UNITED STATES PATENT OFFICE.

DAVID GINGOLD, OF NEW YORK, N. Y.

COASTING DEVICE.

1,075,250.

Specification of Letters Patent.

Patented Oct. 7, 1913.

Application filed December 9, 1912. Serial No. 735,653.

To all whom it may concern:

Be it known that I, DAVID GINGOLD, a citizen of the United States, and a resident of the city of New York, borough of Manhattan, in the county and State of New York, have invented a new and Improved Coasting Device, of which the following is a full, clear, and exact description.

This invention relates to pleasure devices and has particular reference to devices of this character used especially by children in coasting on pavements by the use of wheels, or upon snow and ice by means of runners.

Among the objects of the invention is to improve this class of devices with respect to the steering mechanism and adjustability according to the stature of the user.

Another object of the invention is to facilitate the folding or collapsing operation. The foregoing and other objects of the invention will hereinafter be more fully described and claimed and illustrated in the drawings forming a part of this specification in which like characters of reference indicate corresponding parts in all the views, and in which—

Figure 1 is a side elevation of a preferred embodiment of the invention; Fig. 2 is a front elevation of the same; Fig. 3 is a plan view; Fig. 4 is a side elevation of the same when folded; Fig. 5 is a perspective view showing a modified form of the device in operation; and Fig. 6 is a detail detached.

Referring to the first set of figures for a more specific description of the invention, I show at 10 a platform of any suitable construction upon which the operator is supposed to stand while coasting. Said platform is supported by a pair of trucks, the rear truck comprising an axle 11, rigidly secured to the bottom of the platform and its ends provided with wheels or rollers 12 removably secured thereon by means of nuts 13. The front axle 14 upon which the front wheels 15 are journaled is rigidly secured in any suitable manner as by means of a stirrup 16 to a vertical standard 17 which is adapted to be rotated through a limited degree around the axis of said standard. The means for connecting the front end of the platform for support upon the front axle comprises an extension 18 rigidly secured at the top of the platform and which extends forwardly from the main platform and there provided with a circular notch or socket 18' in which the standard has bearing in its

normal position. The ends 19 of the extension 18 on opposite sides of the notch 18' constitute positive stops against which a block 20, rigidly secured to the front of the standard 17, is adapted to impinge when the standard and front truck are being rotated in either direction. This means provides for safety against the tendency for the device to be turned too quickly and hence it reduces the liability to accident due to this cause.

A yoke 21 providing for the vertical bearing of a collar 22 surrounding the standard 17 is supported upon a horizontal axis, by means of trunnions 23, upon a brace 24 rigidly connected to the aforesaid extension 18. Said brace comprises, in the preferred form, pairs of arms 24 and 25, all having eyes into which the trunnions 23 extend, as shown especially in Figs. 1 and 2. This brace and its connection with the standard 17 constitutes the primary support for the standard, and the weight of the platform is borne normally upon a flange 22' formed upon the lower end of the collar 22. The collar is connected rigidly to the standard in any suitable manner. The form and arrangement of the extension 18, in addition to its functions just described, serve as a means for preventing the rider from standing too close to the front end of the platform. In other words, the occupant of the device will of necessity stand with his feet in the rear of the extension 18 and therefore the likelihood of his taking a header will be lessened.

As shown in Fig. 4, the standard 17 is adapted to fold toward the platform, turning upon the axis of the trunnions 23 in so doing. As a suitable and reliable means to prevent such folding movement when the device is to be used, I provide a strap 26 having an eye 27 at its front end through which the standard extends adjacent the front axle, and having an eye 28 at its rear end adapted to extend over a bolt 29 and there secured by means of a detachable nut 30, said bolt extending through the extension 18 and platform 10. All that is necessary, therefore, to fold the device for storage purposes or transportation is to remove the nut 30 when the strap 26 will be free to slip from the bolt 29 and the front axle and standard will be free to swing on the trunnions 23.

The steering device connected to the upper

portion of the standard comprises preferably a vertical bar 31 having an adjustable connection with the standard by means of a bolt 32 at the upper end of the standard adapted to 5 pass through any one of a series of holes 31' and there secured by means of a nut 33. The portion of the bar 31 which has the holes 31' is preferably flat whereby a more substantial connection is made through the 10 bolt 32 with the standard for steering and controlling purposes. The lower end, however, of the bar, is slipped loosely through an eye bolt 34 so that the only requirement in order to make the vertical adjustment of 15 the bar according to the height of the rider is for the single nut 33 to be removed, and then the bar may be adjusted either up or down to the proper position and the nut then replaced. The handles 35 are shown pivoted 20 at 36 to the upper end of the bar and are adapted to swing upwardly around said pivots, as suggested in Fig. 2, but the downward movement thereof is ended by fixed shoulders or stops 37. This provision of the 25 pivotal handles provides for a better folding of the device for storage purposes and also enables the rider to pass obstacles with greater facility when necessary by reason of the fact either handle may be lifted temporarily in order to pass such obstacle, the 30 temporary control of the device being had through the other handle. It will thus appear that the handles may extend laterally to a much greater extent than the width of 35 the trucks or platform, making the normal control of the device much easier than if the handles were short.

As suggested by Figs. 5 and 6, the rollers 12 and 15 may be replaced by runners or 40 shoes 38, each of the shoes having a hole 38' whereby the shoe may be secured to the proper axle by the use of the same nut 13 which is used to secure the wheel in place. Except as just stated, the other parts of the 45 device in this embodiment of the invention are precisely the same as already described.

The several parts of the invention may be made of any suitable materials and the relative sizes and proportions thereof may be varied to a considerable extent without departing from the spirit of the invention 50 hereinafter claimed.

Having thus described my invention, I claim as new and desire to secure by Letters Patent:—

1. In a coasting device, the combination of a platform, an extension secured upon the front end of the platform, said extension having at its front end a vertical notch and stops on opposite sides thereof, a front axle, 60 a standard rigidly connected to said axle, a brace extending upwardly from said extension, a yoke journaled on a horizontal axis in said braces, the standard being journaled in said yoke, means normally maintaining said standard in a vertical position and extended into said notch in the extension, means to rotate the standard, and a block rigidly secured to the standard and adapted to coöperate with said stops. 70

2. In a coasting device, a platform, means to support the platform including a front axle, a standard rigidly connected to the front axle, a collar secured to the standard and having a flange at its lower end, a yoke 75 journaled upon said collar and resting normally upon said flange, means extending from the platform and supported upon said yoke whereby the front end of the platform is normally supported upon the front axle, 80 means to rotate the standard for steering purposes, and means coöoperating with the said yoke to maintain the standard in normal operative position.

In testimony whereof I have signed my 85 name to this specification in the presence of two subscribing witnesses.

DAVID GINGOLD.
